UNITED STATES PATENT OFFICE

114,063

DESIGN FOR A RESTAURANT COUNTER UNIT

Francis C. Gerardy and Alfred E. Nordland,
Kansas City, Mo.

Application July 26, 1938, Serial No. 78,748

Term of patent 3½ years

To all whom it may concern:

Be it known that we, Francis C. Gerardy and Alfred E. Nordland, citizens of the United States, residing at Kansas City, in the county of Jackson and State of Missouri, have invented a new, original, and ornamental Design for a Restaurant Counter Unit, of which the following is a specification, reference being had to the accompanying drawings, forming part thereof.

In the drawings:

Figure 1 is a view in perspective of a restaurant counter unit showing our new design; and Figure 2 is a top plan view of the same.

We claim:

The ornamental design for a restaurant counter unit, as shown.

FRANCIS C. GERARDY.

ALFRED E. NORDLAND.
